(57) **CLAIM**

The ornamental design for an implant package, as shown and described.

DESCRIPTION

FIG. 1 is a perspective view of an implant package of the present invention;

FIG. 2 is a left side view of the implant package shown in FIG. 1;

FIG. 3 is a rear plan view of the implant package shown in FIG. 1;

FIG. 4 is a front plan view of the implant package shown in FIG. 1;

FIG. 5 is a right side view of the implant package shown in FIG. 1;

FIG. 6 is a top plan view of the implant package shown in FIG. 1;

FIG. 7 is a bottom plan view of the implant package shown in FIG. 1; and,

FIG. 8 is an exploded perspective view of the implant package shown in FIG. 1.

The broken lines shown represent unclaimed subject matter and form no part of the claimed design.
